UNITED STATES PATENT OFFICE.

CHARLES E. SMITH, OF BRIDGEPORT, CONNECTICUT;

DESIGN FOR A BICYCLE-LAMP BRACKET.

SPECIFICATION forming part of Design No. 32,699, dated May 22, 1900.

Application filed April 23, 1900. Serial No. 14,056. Term of patent 7 years.

To all whom it may concern:

Be it known that I, CHARLES E. SMITH, a citizen of the United States, residing at Bridgeport, in the county of Fairfield and State of Connecticut, have invented and produced a new and original Design for a Bicycle-Lamp Bracket; and I do hereby declare the following to be a full, clear, and exact description of the invention, such as will enable others skilled in the art to which it appertains to make and use the same.

The accompanying drawing shows a perspective of my newly-designed lamp-bracket.

As shown in the drawing, the leading or material features of my design are the horizontally-disposed ring-shaped portion 1, open at the rear, as shown at 2, the vertically-disposed ears 3 4, which extend rearwardly in parallelism from the open ends of the ring, and the knee-like member, the upper portion

5 of which extends forwardly from the front of said ring, while the lower part 6 of said member depends in substantially a vertical plane and terminates in a knob-like projection 7, which is bounded by circular confines 8, the said ring 1, ears 3 4, and upper portion 5 of the knee-like member all being contained in the same horizontal plane.

Having thus described my invention, what I claim as new, and desire to secure by Letters Patent, is—

The design for a bicycle-lamp bracket as herein shown and described.

In testimony whereof I affix my signature in presence of two witnesses.

CHARLES E. SMITH.
